CONDUIT

Aaron W. Sherwood, Marietta, Ohio

Application June 20, 1932, Serial No. 618,235

2 Claims. (Cl. 138—81)

This invention relates to hollow tiles or drain conduits and the like.

It is an object of the present invention to provide a sectional construction of hollow tiles or culverts which is inexpensive and simple to manufacture, and which provides for assembly in the field without requiring cumbersome handling apparatus such as is now employed in the placing of heavy tiles.

10 It is a further object to provide a sectional construction for tile of this character in which a number of concrete slabs provided with interlocking members may be readily formed of desired size and shape.

15 Other objects and advantages will be apparent from the following description and the accompanying drawing, in which

Fig. 1 is a perspective view of a hollow tile or culvert pipe embodying the present invention;

20 Fig. 2 is a plan view of a portion of the form which is used in producing the tile slabs;

Fig. 3 is a vertical sectional view on the line 3—3 of Fig. 2;

25 Fig. 4 is a view of one of the tile slabs or sections;

Fig. 5 is a view of a cooperating tile slab adapted to form the adjacent side of the finished conduit;

30 Fig. 6 is a detail view of interlock at the abutting ends of adjacent sections; and

Fig. 7 is a perspective view of a modified form of construction in which a recessed bench is provided in the side slabs.

35 In the making of concrete conduits or culverts it is at present the custom, particularly in the case of larger size conduits, to set up a form in the field, to place the required reinforcing material in the form, and to pour the concrete or other material into the form so that the entire tile or length of culvert is cast integrally. This necessitates accurately setting up the form and removing it after the concrete has set. It is quite difficult with such construction in actual practice to obtain a finished conduit which is of uniform depth throughout and it is not unusual for weak spots to appear. The difficulties are further increased when it is necessary to cast the conduit in mud or over a low lying spot, as the excess of water must be removed so as to insure the proper formation of the conduit.

40 When the conduit is not formed in place, it has been the custom heretofore to lay entire sections of hollow tile or conduit end to end, and particularly with larger sized conduits, this has involved the use of gin poles, tripods or other temporary rigging in order to properly handle the heavy

5 conduits. In many cases a single section of conduit which must be handled in this manner weighs a half a ton, or a ton or more, and consequently such a massive article presents a serious problem with regard to the labor and difficulties of proper handling and its accurate positioning.

10 According to the present invention the conduit lengths are made in sections from flat slabs readily interlocked together. The objectionable features of the prior constructions have thus been successfully solved and it is possible to obtain a 15 conduit of uniform high strength throughout, regardless of the circumstances under which it must be placed, or of the character of the soil in which it is positioned. The weight of the separate 20 pieces is comparatively small as compared to the weight of an entire section of hollow conduit so that the use of external rigging apparatus is not required and the conduit can be placed by ordinary manual handling.

25 Referring to the drawing, which illustrates a preferred embodiment of the invention, there is shown at 10 a frame for constructing the section slabs or blocks according to the present invention. This frame comprises bottom rails 11 to which is 30 suitably attached a horizontal platform 12, the parts being conveniently formed of wooden planks or boards or the like.

35 Side rail members 13 and end rail members 14 are removably supported on the platform 12 and 30 they may, if desired, be located thereon in any convenient manner as by means of dowel pins 15. Additional longitudinally extending members or intermediate rails 16 are laterally spaced a distance corresponding to the width of the slabs to 35 be formed and are removably attached to the end rails 14 as by means of a tongue and groove joint 17. Dividing boards 18 are removably attached between the members 16 and the side rails, being spaced apart a distance corresponding to the 40 lengths of the blocks to be formed. These boards 18 are likewise made removable from the platform, and, in conjunction with the members 16, and the side and end rails, form a plurality of 45 independent molds, each adapted to receive the concrete or similar forming material and to form an independent tile side or slab.

50 Wedge shaped projections 20 are provided on the side rails 13 and similar projections 21 are provided extending inwardly from some of the 50 members 16. These wedge shaped members are adapted to form mortises in the cast slabs. Correspondingly tapered recesses 22 are formed in certain of the members 16 in order to provide tenons on the cooperating cast slabs, permitting 55

the ready assembly of the slabs into a compact whole. As shown, each of the slabs comprises two mortises 29 or tenons 27 on each lateral edge. It will be obvious that the slabs can be made any desired length, and provided with any desired number of joints. The complete mold provides for the simultaneous casting of a number of slabs sufficient to form several complete conduit lengths, the form of construction shown being so arranged as to provide several rows of four slabs, each row producing a set of slabs or blocks for forming one complete hollow conduit section.

In order to form a conduit of reinforced construction, the individual sections are provided with reinforcing such as the wire netting shown at 25. This may be placed in the form prior to or during the filling thereof with concrete. Special reinforcing may be used at the positions of the mortised projections. The tops of the side and end rails lie in a single plane so as to serve as guides for a scraper board to scrape off the excess concrete and to insure the production of sections of uniform characteristics. The walls of the several portions of the frame are slightly tapered so as to permit their withdrawal after the setting of the concrete.

Following the removal of the form pieces, the individual blocks are removed and are then ready to be assembled into the conduit. The precast slabs 26 and 28 are joined and interlocked together to form complete tile or conduit lengths which are preferably rectangular in cross section, although they may be of any shape desired. The ends of the blocks or slabs, as well as their sides, may if desired be provided with interlocking mortise and tenon connections so that the various lengths of built up conduit may be securely interlocked and held to one another. Fig. 6 illustrates such construction, suitable for the top and bottom slabs, the slabs of one built up conduit section having projecting tongues 31 at one end, while the slabs of the abutting section have cooperating mortises interlocking therewith, the end mortises and tenons being provided by correspondingly shaped irregularities in the end rails 14, and in the boards 18 which are of course then made much wider so they may include the depressions required.

As shown in Fig. 7, the outer edge of the main body of the top slab may rest on the top of the side slabs by providing a bench 32 which relieves the tenons from the greater part of the weight of the top slab. In such an arrangement the rails would be of the proper dimensions to produce the top and bottom slabs, while the recessed portions of the side slabs may be provided by correspondingly shaped filler pieces for the mold rails and preferably separable from the mold rails so the mold portions can be readily removed from the cast slabs.

The invention also provides for forming a block for drainage purposes in which some or all of the sides are perforated. These perforations can be easily produced by providing dowel pins 30 in the platform 12 so tapered as to be readily pulled up out of the partly set concrete. These pins can be used when desired, and the hole in platform 12 suitably plugged when a perforated section is not desired.

By reason of the sectional construction as herein provided, it is possible to easily set up the particular type of hollow conduit, as regards reinforcing, length, and drainage facilities, that is desired in any particular instance. In instances where it is desirable to prevent the escape of

water from the conduit, the joints can be effectively sealed by a cement grout or the like although in many cases where the placed conduit is back filled with gravel it is not desirable to seal the conduit too tightly. In the construction of a conduit or culvert, one of the slabs 26 may be first laid in place with the narrower sides of the tenons uppermost. The two side slabs 28 are then interlocked with it and the top slab applied, the wedge like or tapered character of the tenons and mortises holding the side slabs from either outward or inward movement. The next conduit section is then built up in the same way, and where the ends of the adjacent sections are dovetailed together by joints such as are shown in Fig. 6 certain of the slabs are interlocked with an abutting section at the same time they are interlocked with an adjoining side slab. Sufficient clearance is provided at the dovetailed joints so that the slabs are very readily moved into place.

The individual sections or slabs, even in the larger sizes, are not of such excessive weight as to require the handling apparatus heretofore necessary. Furthermore the conduit can be built up in any soil with a minimum of preparatory expense. The entire expense of constructing conduit from blocks made according to the present invention is materially reduced and simplified as the sections are all preformed preferably at a central point where the work can be done effectively and cheaply. Individual sections of required sizes, properly marked to indicate their position and length, can be furnished to the engineer in the field who thus dispenses entirely with the usual forms and with the mixing of concrete in an inefficient and relatively expensive manner in a small mixer in the field. Furthermore the construction of the blocks is made more uniform and better assurance is given of the product being of the proper strength.

While the product and method and the apparatus employed therefor as herein described constitute preferred embodiments of the invention, it is to be understood that the invention is not limited precisely thereto, and that changes may be made therein without departing from the scope of the invention which is defined in the appended claims.

What is claimed is:

1. A built-up conduit of rectangular cross section of the character described, comprising horizontal top and bottom and two side precast concrete slabs each provided with an interlocking dovetail portion on each longitudinal edge thereof of cooperating with an interlocking dovetail portion of an adjoining slab and assembled together to form a hollow structure each outer side of which lies in a single plane, the dovetail portion of the top and bottom slabs having substantially vertical end faces interlocking with substantially vertical end faces of the dovetail portions of the side slabs to prevent any outward movement of the side slabs and to provide for assembly of the top slab upon the positioned side slabs merely by vertical lowering of the top slab, each side slab having upper and lower horizontally extending bench portions extending beyond the dovetail portions thereof and cooperating with the dovetail portions thereof to constitute a support extending the entire length of the side slab for the edges of the top and bottom slabs, said top and bottom slabs having end projections adapted for interlocking engagement with similar complementary projections of other similar top and bot-

tom slabs assembled end to end therewith and adapted for assembly merely by vertical lowering movement of one horizontal slab in extension of the other.

5 2. A built-up conduit of rectangular cross section of the character described, comprising horizontal top and bottom precast concrete slabs connected by opposed vertical precast concrete side slabs, each of said slabs having an interlocking dovetail portion on each longitudinal edge thereof cooperating with an interlocking dovetail portion of an adjoining slab and assembled together to form a hollow structure each outer and inner side of which lies in a single plane, the dove-tailed portions of the top and bottom slabs hav-

ing substantially vertical end faces interlocking with substantially vertical end faces of the dovetail portions of the side slabs to prevent any outward movement of the side slabs and to provide for assembly of the top slab upon the positioned side slabs merely by vertical lowering of the top slab, a horizontal slab of the conduit also having a dovetail interlock at a laterally extending end thereof for engagement with an abutting slab, said vertical side slabs each having a horizontal bench extending from the dovetail portion thereof and forming a rest for the edge of the horizontal slabs.
